YARN BOBBIN

Jacob Gomberg, Chicago, Ill.

Application July 2, 1942, Serial No. 449,424

1 Claim. (Cl. 242—96)

The invention relates to bobbins particularly to bobbins for holding yarns, threads or strings.

It is an object of the invention to provide a bobbin which securely holds the yarn but permits unwinding thereof in a facile manner.

A further object constitutes the provision of a bobbin which is made of a flexible material and comprises an elongated body member having a semi-circular cut out portion at one end and a circular opening at the other end there being a slit between the opening and the edge of the other end permitting insertion or unwinding of the yarn by laterally springing the terminal portions of said other end.

With these and other objects in view which will become apparent from a perusal of the invention the latter comprises the means described in the following specification, particularly pointed out in the claim forming a part thereof and illustrated in the accompanying drawing, in which

Fig. 1 is a front view of the bobbin constructed in accordance with my invention.

Fig. 2 is a section on line 2—2 of Fig. 1, and

Fig. 3 is a bottom plan view.

Referring to the drawing 10 designates an elongated body member made of cellulose acetate material or any other material which has springy or resilient properties.

As shown the member 10 has a semi-circular cut-out portion 11 at the end portion 12 and the other end 13 is semi-circular. A circular open-

ing 14 is concentrically arranged at the end 13 and a slit 15 between the opening 14 and the terminal edge of the end 13 defines two prongs 16 and 17 which may be separated by flexing.

Upon cessation of the pressure the prongs resume normal position.

It is evident that the yarn is wound around the body member by being threaded through the slit 15, and wound on the edge of the cut out portion 11, again threaded through the slit 15 and wound on the edge 11 and this continued until the entire yarn is wound on the member.

If desired differently colored yarns may be wound on the member 10 or a plurality of members may be employed each having yarn of different color where variegated articles are to be produced.

I claim:

20 A yarn bobbin comprising a body member of flexible material provided at one end with a pair of prongs adapted to contact one another at the free end and defining a circular opening, said prong ends being in the same plane as said body member and separable by flexing in a plane at right angles to the plane of said body member and at the longitudinal center thereof and means at the other end of said body member for receiving the turns of the yarn coiled around the body portion through the opening, said prongs controlling the winding and unwinding of the coil.

JACOB GOMBERG.
